UNITED STATES PATENT OFFICE.

GRAZIANO APPIANI, OF TREVISO, ITALY.

OPTICAL PROJECTING APPARATUS.

1,080,528.

Specification of Letters Patent.

Patented Dec. 9, 1913.

Application filed August 13, 1912. Serial No. 714,767.

To all whom it may concern:

Be it known that I, GRAZIANO APPIANI, subject of the King of Italy, residing at Treviso, Italy, have invented new and useful 5 Improvements in Optical Projecting Apparatus, of which the following is a specification.

Ordinarily, between the lens which serves to condense the luminous rays of the lamp 10 in kinematographic projecting apparatus and the film to be projected, a vessel filled with water or any other liquid is interposed and arranged with the object of preventing the overheating of the film, which might 15 result in its combustion. These vessels are ordinarily composed of small cases or boxes or of transparent bottles. The water, or other liquid contained in such vessels evaporates comparatively readily, which affects 20 the regularity of the operation of the kinematographic apparatus, and it has consequently been proposed to employ apparatus whereby the gradual heating of the water or other liquid imparts to the liquid itself a 25 continuous ascending and descending movement between such vessels and a vessel arranged at a higher level and connected thereto by tubes, and by reason of which the liquid in the transparent vessel undergoes a 30 cooling action.

Hitherto the connecting tubes between the transparent vessel and the vessel at a higher level to which same is connected have been situated so as to project into the part of the 35 transparent vessel which is interposed between the lamp of the kinematographic apparatus and the film the picture on which is to be projected on the screen, that is to say in the path of travel of the rays of light for 40 projecting such picture, and although said tubes are of glass they present such an obstacle as to materially affect the perfect projection of the pictures on the screen. The relative positions of the two vessels and the 45 connections between same have further been such as to materially impede the circulation of liquid between them and also to give rise to an ebullition of the liquid within the portion of the transparent vessel through 50 which the rays of light pass and so further impair the perfection of the pictures projected thereby from the film bearing means on to the screen. According to the present invention I avoid these disadvantages and I 55 make the connections between the transparent vessel and the vessel with which the

circulation of liquid is to be maintained so that the tubes employed do not project into the part of the transparent vessel through which the rays of light for the projection of the picture on to the film pass, while the circulation of liquid between the vessels is in no way impeded and no ebullition of the liquid occurs in the transparent vessel.

Figure 1 of the accompanying drawing is 60 a transverse section of a suitable form of apparatus for carrying the invention into effect. Fig. 2 is a diagrammatic sectional view showing the kinematograph apparatus with the device in position.

Above a transparent vessel *a* of any form, a second vessel *b* is arranged. This second vessel may form one with the first vessel, or be simply arranged above it. Communication between the two vessels is established 65 by means of two tubes *c* and *g*. The tube *c*, of glass, metal or any other suitable material, the lower extremity *d* of which is situated at the upper part of the lower transparent vessel, passes through a stopper *e*, of india rubber, cork, or other suitable material, which closes the opening of vessel *a*, projects through an opening in the upper vessel *b* and at its upper extremity *f* terminates at the highest part of the upper vessel *b*. The other tube *g*, which also passes 70 through the stopper *e*, of the opening in the vessel *b*, has its lower extremity *h* situated a little below the lower extremity *d* of the tube *c*; and its upper extremity *i* only 75 attains or slightly exceeds the upper surface of the stopper *e*.

It is apparent that when the water or other liquid contained in the vessel *a* becomes heated, by a physical law it ascends 80 through the tube *c* and enters the upper vessel *b*, where the temperature is naturally lower, and whence, consequently, a corresponding quantity of cooler liquid descends by tube *g* into the vessel *a*. A continuous 85 circulation is thus established of warmer liquid which ascends from the lower transparent vessel *a* and is delivered into the upper vessel *b* (which need not be transparent), and of cooler liquid which descends 90 from the upper vessel *b* into the lower vessel *a*.

The cooling of the liquid in the transparent lower vessel *a* will naturally be the more rapid the larger the upper vessel *b* is 95 made in proportion to the lower vessel *a*; by these means the result is attained of al-

ways keeping the vessel filled with water or other liquid which serves as a shield against heat between the condensing lens and the film, at such a temperature that the 5 inconveniences hereinbefore indicated are avoided, that is to say the necessity of changing the said vessels or the liquid which they contain, on account of the evaporation which, without the use of the present apparatus, will occur in said vessels. The result 10 therefore is attained of employing vessels which it is neither necessary to change nor to replace the liquid which they contain. The danger of conflagration or of damage to 15 the films is thus avoided, by keeping cool the projecting apparatus, which becoming heated often occasions the ignition of the films, and consequently results in a conflagration. The bottle may not only fulfil the function of 20 a shield against heat between the lenses and the projecting apparatus, but it might also at the same time act both as the lens and the protecting shield against heat between the lantern, the light and the projecting appa- 25 ratus.

As the tubes *c* and *g* only extend into the upper portion of the vessel *a* and the latter when in use is arranged so that only its lower portion is interposed between the condensing lens of the kinematographic apparatus and the film bearing the picture to be projected on the screen, said tubes will offer no obstacle to the free passage of light through the vessel and the projection of the 30 picture will consequently be in no way impaired.

If desired, ice or other refrigerating agent might be placed in the upper vessel, or such upper vessel be constantly maintained cool 40 by any of the known refrigerating means; which could not be effected in the lower vessel, without great difficulty, for this latter must necessarily be kept perfectly transparent.

45 Fig. 2 of the accompanying drawing illustrates the manner in which the bottle *a* with the upper vessel *b* may be arranged in front of the box *m* containing the lantern and the light condensing lens. Said bottle which 50 as usual serves as a transparent protector against heat for the apparatus *n* in which the film unwinds, may be supported by a bracket *o* and a support *p*.

What I claim as my invention, and desire 55 to secure by Letters Patent, is—

1. In apparatus of the class described, in

combination, a transparent vessel adapted to be positioned between the source of light of a kinematograph and the film, a vessel positioned at a higher level than said transparent vessel and tubes extending between said vessels whereby liquid contained within said vessels may circulate, the ends of the tubes which extend within said transparent vessel being positioned out of the path of the rays of light which pass from the source of light to the film. 60

2. In apparatus of the class described, in combination, a transparent vessel adapted to be positioned between the source of light of a kinematograph and the film, a vessel positioned at a higher level than said transparent vessel and tubes extending between said vessels whereby liquid contained within said vessels may circulate, the ends of the tubes which extend within said transparent vessel terminating in the upper part thereof, whereby said tubes will be positioned out of the path of the rays of light which pass from the source of light to the film. 70

3. In apparatus of the class described, in combination, a transparent vessel adapted to be positioned between the source of light of a kinematograph and the film, a vessel positioned directly above said transparent vessel 85 and tubes extending between said vessels whereby liquid contained within said vessels may circulate, the ends of the tubes which extend within said transparent vessel being positioned out of the path of the rays of light which pass from the source of light to the film. 90

4. In apparatus of the class described, in combination, a transparent vessel adapted to be positioned between the source of light of a kinematograph and the film, a vessel positioned at a higher level than said transparent vessel and tubes extending between said vessels whereby liquid contained within said vessels may circulate, said tubes being straight throughout their length, the ends of the tubes which extend within said transparent vessel being positioned out of the path of the rays of light which pass from the source of light to the film. 95

In testimony whereof I have signed my name to this specification in the presence of two subscribing witnesses.

GRAZIANO APPIANI. [L. S.]
